UNITED STATES PATENT OFFICE.

GEORGE COURTS PARKER, OF BUCHANAN, TENNESSEE.

PLAITING-MACHINE.

SPECIFICATION forming part of Letters Patent No. 359,810, dated March 22, 1887.

Application filed December 31, 1886. Serial No. 223,148. (No model.)

To all whom it may concern:

Be it known that I, GEORGE COURTS PARKER, of Buchanan, in the county of Henry and State of Tennessee, have invented a new and 5 Improved Plaister, of which the following is a full, clear, and exact description.

This invention relates to plaiters, the object of the invention being to provide an implement which may be used for the purpose of 10 plaiting goods after said goods have been made up into wearing-apparel, as will be hereinafter more fully explained.

Reference is to be had to the accompanying drawings, forming a part of this specification, 15 in which similar figures of reference indicate corresponding parts in both the views.

Figure 1 is a perspective view of my improved form of plaister, the parts being represented as they appear when in plaiting position; and Fig. 2 is a cross-sectional view of 20 the plaister, representing the parts as they appear after the plaiting-frame has been folded over onto the ironing-bed for the purpose of setting the plaits.

25 In constructing such a plaister as the one illustrated in the drawings above referred to, I provide a frame, 10, made up of side and end pieces properly united, and in the open space between said side and end pieces I arrange a perforated metal plate, 11. Sheetimg or other textile covering is stretched over the frame, and held to the edges thereof by tacks 2, that pass through a retaining-tape, 3.

To the outer edge of the frame 10 I hinge 31 metallic arms 12, the ends of which are united by a longitudinal strip, 13, each of the arms 12 being bent at right angles at the points 4, so that they may be folded to rest close against the upper face of the fabric that is stretched 36 upon the frame 10, in which position they are held by turn-buttons 15, that are arranged above washers or supports 16, upon which the ends of the arms 12 rest. Between the arms 12 I stretch three or more tapes, 20, said tapes 45 being held taut by means of elastic strips 21, arranged as best shown in Fig. 1.

To the rear edge of the frame 10 I hinge an ironing-board, 30. The upper face of said board is covered by any soft material, as in 50 the ordinary form of ironing-board, and in order that the frame 10 may fit close against the upper face of the material stretched across the

upper face of the board I form said board with a groove, 31, that is so placed that when the parts are folded to the position in which they are shown in Fig. 2 the strip 13 will rest 55 within said groove.

To the forward edge of the frame 10 I secure a hook, 6, that is arranged to engage with an eye, 7, as shown in Fig. 2.

To operation, the arms 12 are turned back and the material to be plaited, whether it be attached to the garment or not, is placed across the upper face of the material carried by the frame 10. The arms 12 are then returned to 60 the position in which they are shown in Fig. 1, and the turn-buttons 15 are moved so as to hold said arms in the position named.

A double-bladed knife, such as is ordinarily used in plaiting, is utilized for the purpose of 70 turning the plaits beneath the strips 20. After such plaits have been properly turned the frame 10 is thrown over upon the upper face of the board 30. The plaits are moistened by passing a sponge over the then upper surface 75 of the perforated sheet 11, and a hot iron is passed over said sheet, thus setting the plaits, as will be readily understood.

One of the greatest advantages arising from 80 the use of such a plaister as has been described is that plaits may be laid upon material that is already made up into garments, which was not possible with any of the old forms of plaiters.

Another great advantage arising from the 85 use of this plaister is that the plaits can be renewed or replaited without removing from the garment, and as a consequence cotton, as well as woolen, goods may be plaited; and if the plaits are disarranged by washing they can be 90 replaited without removing from garment.

Having thus fully described my invention, I claim as new and desire to secure by Letters Patent—

1. In a plaister, the combination, with the 95 frame 10, the arms 12, having their outer ends bent at right angles, as shown at 4, and hinged to the edge of the frame, and the longitudinal strip 13, connecting the inner ends of the arms 12, the strips 20, carried by the arms, and the 100 turn-buttons on the frame engaging the outer ends of the arms 12 at their sides, of the ironing-board 30, hinged to the frame 10 and folding over the strips and arms on frame 10, be-

tween the turn-buttons, substantially as set forth.

2. In a plaiter, the combination, with an ironing-board formed with a recess, 31, of a frame, 10, hinged thereto, arms 12, hinged to the frame, strips 20, carried by the arms, and provided with elastic connections 21, and turn-buttons

15, arranged to engage the extending ends of the arms, substantially as described.

GEORGE COURTS PARKER.
